CLAIM

The ornamental design for a tool trolley, as shown and described.

DESCRIPTION

FIG. 1 is a top, front, left side perspective view of a tool trolley showing my new design;

FIG. 2 is a right side elevational view thereof;

FIG. 3 is a left side elevational view thereof;

FIG. 4 is a rear side elevational view thereof;

FIG. 5 is a front side elevational view thereof;

FIG. 6 is a top plan view thereof; and

FIG. 7 is a bottom plan view thereof.

FIG. 8 is a top, front, left side perspective view of the tool trolley of FIG. 1 showing the handles unfolded and with the trays spaced along the handles;

FIG. 9 is a right side elevational view thereof;

FIG. 10 is a left side elevational view thereof;

FIG. 11 is a rear side elevational view thereof;

FIG. 12 is a front side elevational view thereof; and

FIG. 13 is a top plan view thereof, the bottom plan view being the same as in FIG. 7.

FIG. 14 is a top, front, left side perspective view of the tool trolley of FIG. 8 showing the trays positioned laterally outwardly;

FIG. 15 is a right side elevational view thereof;

FIG. 16 is a left side elevational view thereof;

FIG. 17 is a rear side elevational view thereof;

FIG. 18 is a front side elevational view thereof;

FIG. 19 is a top plan view thereof; and,

FIG. 20 is a bottom plan view thereof.

The broken lines in FIG. 7 and FIG. 20 identify areas of environment and are not part of the claimed design.

1 Claim, 20 Drawing Sheets
